UNITED STATES PATENT OFFICE.

WILLIAM ALBERT WHITE, OF NEW YORK, N. Y.

ATOMIZER.

1,227,352.

Specification of Letters Patent.

Patented May 22, 1917.

Application filed November 15, 1913. Serial No. 801,122.

To all whom it may concern:

Be it known that I, WILLIAM A. WHITE, a citizen of the United States, and resident of the borough of Manhattan, in the city, 5 county, and State of New York, have invented certain new and useful Improvements in Atomizers, of which the following is a specification.

This invention relates to an improved atomizer which is capable of employment as an oil burner, and to a furnace front having an air supply capable of coöperating with the atomized fuel delivery in a novel and efficient manner.

15 In the drawing:

Figure 1 is a longitudinal section of my improved atomizer or fuel burner tube.

Fig. 2 is a section on the line 2—2 of Fig. 1.

20 Fig. 3 is a face view of the atomizer plug.

Fig. 4 is a side sectional view of a furnace front with burner tube axially disposed therein and air passages tangentially directed thereto, and

25 Fig. 5 is a partial sectional elevation of the furnace front on the line 5—5 of Fig. 4 showing some of the air passages.

My improved atomizer or burner tube is constructed in manner to deliver from its 30 nozzle atomized fuel swirling in one direction and the furnace front is provided with air passages directed tangentially toward said burner tube in a manner to convey air toward a central air supply tube in a swirl 35 moving oppositely to the movement of the fuel that issues from the atomizer nozzle.

The oppositely moving streams of fuel and air meeting in a supply tube about the burner nozzle become more thoroughly com- 40 mingled than if traveling in the same direction, with the result that a high state of combustion is attained.

The atomizer construction comprises a burner tube 1, having an oil feed 2 at one 45 end thereof. Near its forward end said tube has an internal shoulder 3 forming a seat for a coiled spring 4 that is inserted in said tube. A plug 5 fits slidably within tube 1, lying against spring 4, which serves 50 as an elastic seat therefor, and said plug has a stem 6 that is entered as a guide within the tubular formation of said spring. The face of plug 5 is in form of a double cone. That is to say, said face consists of 55 the frusto-conical portion 7 continuing from

the outer perimeter of plug 5, and a central reduced cone 8 extends from the face of said portion, said cone being inset from the inner perimeter of the frusto-conical portion 7. A cap 9 is adapted to be fitted upon the inner end of tube 1, as by male and female screw threads upon these respective members. Said cap 9 has a discharge orifice 10 at its forward end, and has an internal conical wall 11, anterior to said orifice, to seat 60 the frusto-conical portion 7, under the tension of spring 4. Under these circumstances, an annular space 12 exists between cone 8 and the surrounding wall 11, this space being intended for the passage of fuel 70 to the orifice. Channels 13, along the periphery of plug 5, continue into diminishing grooves 14 extending tangentially across the face of frusto-conical portion 7, and thus direct liquid fuel from the tube 1 to the 75 space 12 aforesaid. The fuel being under pressure, enters said space in whirling streams, and issues from the orifice as a swirling mist.

The said burner tube or atomizer is fitted 80 axially in a furnace front which is composed of the separated plates 15, 16, with air passages 17 extending from inlets 18 at the periphery of plate 15, to a central space 18^a in said furnace front surrounding said 85 burner tube. A constricted air supply tube 19 surrounds the nozzle of the burner tube, and forms the communication between said central space 18^a and the furnace interior. The inwardly directed air passages 17 are 90 bounded by partitions 20, which, instead of centering toward the burner tube, are arranged tangentially with respect thereto, whereby air traversing passages 17 whirls about tube 1 in space 18^a, and passes through 95 air supply tube 19 with a swirling motion. It should be particularly noted that the tangent of the passages 17 is in the opposite direction to the tangent of the grooves 14 in the atomizer plug, so that the whirling fuel 100 streams and the whirling air supply are moving oppositely as they meet in tube 19.

The burner tube 1 has a jacket 21, spaced therefrom, and with perforations 22 extending forwardly and tangentially therethrough 105 with respect to said tube, the tangent of said perforations being opposite to the tangent of the grooves 14 in the atomizer plug. Air from the main air supply enters said jacket through the perforations, serving to 110

cool the burner tube, and whirls about said burner tube, issuing from said jacket, about the burner nozzle, with a whirling motion opposite to the direction of movement of 5 the atomized fuel, supplying at the genesis of the flame a suitable air admixture.

An approximately cone-faced valve 23 is 10 slidable over jacket 21, to regulate the passing of air through tube 19, said valve having actuating rods 24. Also slidable over jacket 21, at its forward end, is an air deflector 25, which has rods 26 to control its movement.

I claim:

- 15 1. An atomizer consisting of a tube with a cap fitting removably thereover, said cap having a central orifice of diameter greater than its axial depth, a plug in said tube comprising a cylindrical portion and a frusto-conical portion, said cylindrical portion having longitudinal peripheral grooves and said frusto-conical portion having tangential grooves in its face which communicate with said longitudinal grooves, and a diminished cone continuing from said frusto-conical portion, in fixed relation therewith, toward said orifice; said cap forming a conical chamber anterior to said orifice, the wall of said chamber providing a seat for 20 said frusto-conical portion, and providing a space surrounding said diminished cone to form a permanent passage between said tangential grooves and said orifice, whereby fluid enters said passage at an obtuse angle from the grooves, follows therefrom in the same conical zone into the aforesaid conical chamber, and forms therein a whirling film centering at the orifice for lateral dispersal 25 upon emission from said orifice, and a spring seating in said tube and bearing against said plug, within the aforesaid clearance, to firmly hold its frusto-conical portion against said conical chamber wall.
- 30 2. An atomizer consisting of a tube with a cap fitting removably thereover, said cap having a central orifice of diameter greater than its axial depth, a plug in said tube comprising a cylindrical portion and a frusto-conical portion, said cylindrical portion having longitudinal peripheral grooves and said frusto-conical portion having tangential grooves in its face which communicate with said longitudinal grooves, and a diminished cone continuing from said frusto-conical portion, in fixed relation therewith, toward said orifice; said cap forming a conical chamber anterior to said orifice, the wall of said chamber providing a seat for said frusto-conical portion, and providing a space surrounding said diminished cone to form a permanent passage between said tangential grooves and said orifice, whereby fluid enters said passage at an obtuse angle from the grooves, follows therefrom in the same conical zone into the aforesaid conical chamber, and forms therein a whirling film centering at the orifice for lateral dispersal 35 upon emission from said orifice, and a spring seating in said tube and bearing against said plug, within the aforesaid clearance, to firmly hold its frusto-conical portion against said conical chamber wall.
- 35 3. An atomizer consisting of a tube with a cap fitting removably thereover, said cap having a central orifice of diameter greater than its axial depth, a plug in said tube comprising a cylindrical portion and a frusto-conical portion, said cylindrical portion having longitudinal peripheral grooves and said frusto-conical portion having tangential grooves in its face which communicate with said longitudinal grooves, and a diminished cone continuing from said frusto-conical portion, in fixed relation therewith, toward said orifice; said cap forming a conical chamber anterior to said orifice, the wall of said chamber providing a seat for said frusto-conical portion, and providing a space surrounding said diminished cone to form a permanent passage between said tangential grooves and said orifice, whereby fluid enters said passage at an obtuse angle from the grooves, follows therefrom in the same conical zone into the aforesaid conical chamber, and forms therein a whirling film centering at the orifice for lateral dispersal 40 upon emission from said orifice, and a spring seating in said tube and bearing against said plug, within the aforesaid clearance, to firmly hold its frusto-conical portion against said conical chamber wall.

frusto-conical portion against said conical chamber wall.

2. An atomizer consisting of a tube with a cap fitting removably thereover, said cap having a central orifice of diameter greater than its axial depth, a plug in said tube comprising a cylindrical portion and a frusto-conical portion, said cylindrical portion having longitudinal peripheral grooves and said frusto-conical portion having tangential grooves in its face which communicate with said longitudinal grooves, and a diminished cone continuing from said frusto-conical portion, in fixed relation therewith, toward said orifice, the rearward portion of said plug being of reduced diameter to provide a clearance between it and the tube; said cap forming a conical chamber anterior to said orifice, the wall of said chamber providing a seat for said frusto-conical portion, and providing a space surrounding said diminished cone to form a permanent passage between said tangential grooves and said orifice, whereby fluid enters said passage at an obtuse angle from the grooves, follows therefrom in the same conical zone into the aforesaid conical chamber, and forms therein a whirling film centering at the orifice for lateral dispersal upon emission from said orifice, and a spring seating in said tube and bearing against said plug, within the aforesaid clearance, to firmly hold its frusto-conical portion against said conical chamber wall.

Signed at the borough of Manhattan, in the city, county, and State of New York, this 13th day of November, A. D. 1913.
